[57] CLAIM

The ornamental design for a home/office stapler, as shown and described.

DESCRIPTION

FIG. 1 is a perspective view of a home/office stapler showing our new design;

FIG. 2 is a left side elevational view thereof;

FIG. 3 is the right side elevational view thereof;

FIG. 4 is a top plan view of the stapler;

FIG. 5 is a plan bottom view thereof;

FIG. 6 is a front elevational view thereof;

FIG. 7 is a rear elevational view thereof;

FIG. 8 is a perspective view of an alternate embodiment of FIG. 1;

FIG. 9 is a left side elevational view of FIG. 8;

FIG. 10 is right side elevational view of FIG. 8;

FIG. 11 is a top plan view FIG. 8;

FIG. 12 is a bottom plan view of FIG. 8;

FIG. 13 is a front elevational view of FIG. 8; and

FIG. 14 is a rear elevational view of FIG. 8.
